CLAIM

The ornamental design for an ergonomic notebook stand, as shown and described.

DESCRIPTION

FIG. 1 is a perspective view of an ergonomic notebook stand, showing my new design; the broken lines are for environmental purposes only and form no part of the claimed design.

FIG. 2 is an exploded parts view thereof.

FIG. 3 is a front plan view thereof.

FIG. 4 is a back plan view thereof.

FIG. 5 is a side view thereof.

FIG. 6 is a side elevational view showing the side not shown in FIG. 5.

FIG. 7 is a top view thereof.

FIG. 8 is a bottom view thereof.

FIG. 9 is a side view thereof as shown in FIG. 5, in a second position.

FIG. 10 is an opposite side view thereof as shown in FIG. 6, in a second position.

The broken-line showing of environmental structure in FIGS. 1, 4, 5, 6, 7, and 8 is for illustrative purposes only and forms no part of the claimed design.
